HORSESHOE GAME GOAL

Cecil R. Smith, 719 Old Orchard,
Excelsior Springs, Mo. 64024

Filed Jan. 21, 1969, Ser. No. 15,424

Term of patent 14 years

Int. Cl. D21—01

U.S. Cl. D34—5

FIGURE 1.

FIGURE 2.

FIGURE 3.

FIGURE 4.

FIGURE 5.

FIGURE 1 is a plan view of a horseshoe game goal showing my new design;

FIGURE 2 is a side elevation thereof; the opposite side is a mirror image of the side shown;

FIGURE 3 is a front elevation thereof;

FIGURE 4 is a sectional view taken on lines 4—4 of FIGURE 1;

FIGURE 5 is a rear elevation thereof; and

FIGURE 6 is a sectional view taken on line 6—6 of FIGURE 1.

I claim:

The ornamental design for a horseshoe game goal, as shown and described.
